UNITED STATES PATENT OFFICE.

GEORGE T. SMILEY AND WALTER R. OHSE, OF HOUSTON, TEXAS.

REFRIGERATING APPARATUS.

Application filed October 28, 1927. Serial No. 229,366.

This invention relates to refrigeration devices and has for an object to provide a plurality of circulating coils disposed in parallel with respect to a series of flues, the coils being adapted for the passage of a cooling fluid therethrough whereby to cause a lowering of the temperature within the flues and thus create a circulation of the air within the refrigerating compartment and which will be maintained at a desired uniform temperature by reason of its contact with the coils.

A further object of the invention is to provide a plurality of refrigerating units within a compartment and composed of a series of flues inclined in a direction toward a common point in the compartment at which time the cooler air from the flues is discharged and which upon coming into contact with the warmer air in the compartment remote from the refrigerating devices, operates to cause a circulation of the air so that the entire volume thereof will from time to time come into contact with the refrigerating unit and thus lower the temperature of the same.

A still further object is to provide an apparatus of this character of simple and practical construction, efficient and reliable in performance, economical in operation, inexpensive to manufacture and install and otherwise well adapted for the purpose for which the same is intended.

Other objects and advantages reside in the special construction and combination of the various elements comprising the invention, reference being had to the accompanying drawings forming a part hereof, wherein:

Figure 1 is a vertical sectional view through a refrigerating compartment equipped with a pair of refrigerating units constructed in accordance with our invention.

Figure 2 is a horizontal sectional view taken substantially along line 2-2 of Figure 1.

Figure 3 is a similar view taken substantially along the line 3-3 of Figure 1 and showing the bottom plan view of one of the division plates forming one of the flues,

Figure 4 is a vertical transverse sectional view taken along the line 4-4 of Figure 1 and

Figure 5 is a perspective view of one of the division plates.

Referring now to the drawings in detail, we have shown our invention adapted for use

in connection with a refrigerating compartment indicated at 5 which may be of any suitable shape or construction, the top of which, at its inner side is provided with a plurality of transversely extending beams 6 forming a support for the downwardly extending refrigerator unit supporting rods 7. These rods constitute supporting means for the series of division plates 8 of a rectangular formation having each corner notched as at 9 forming a seat for the rod whereby upon engagement therewith to prevent longitudinal or transverse movement of the plate within the compartment.

The division plates are arranged in spaced parallel relation at an inclined angle from a horizontal plane as more clearly illustrated in Figure 1 of the drawings, the space between the plates constituting a flue and arranged with the discharge end of each unit contained within the compartment extending toward the center of the compartment.

A section of pipe coil 10 is arranged within each of these flues and disposed in the upper portion thereof adjacent the underside of the division plates forming the top of the flue, the pipe section forming the coil extending in spaced parallel relation at right angles to the direction of travel of air through the flue. The ends of the coil of each flue are connected by vertical sections 11 to each adjacent section of coil immediately above and beneath the same.

The coil at the lowermost flue of one of the refrigerating units is connected by a pipe 12 extending to the coil of the uppermost flue of the adjacent refrigerating unit. An intake pipe 13 is connected to the coil at the uppermost flue of one of the refrigerating units, said intake pipe having a control valve 14 interposed therein and the lowermost coil of the opposite refrigerating unit is connected by a discharge pipe 14 leading from the compartment.

It will be apparent that upon feeding a cooling fluid into the intake pipe 13 that the passage of the same through the coil section 10 arranged within the flue will thereby have a tendency to cool the air through the flues, which upon being cooled will have a tendency to flow downwardly through the flues toward the center of the refrigerating compartment. The cool air from the flues, coming into contact with the relatively warmer air at the center of the compartment will cause the warm air to move upwardly to

- ward the top of the compartment, the suction of the air traveling through the flues thus causing the warm air at the top of the compartment to be drawn toward the intake 5 end of the flues whereupon during the continuous operation of the device the air throughout the compartment will eventually become uniformly cooled to a relatively low temperature.
- 10 The feeding of the cooling liquid into the coil may be controlled in any suitable manner as by means of the manually operable valve 14 or in any other suitable manner depending upon the particular condition 15 under which the apparatus is operated.

It will be understood that while the present disclosure of the invention shows a refrigerating compartment equipped with two of the refrigerating units constructed in 20 accordance with my invention, any suitable number of these units may be installed within the compartment to meet particular conditions.

It is obvious that the invention is susceptible of various changes and modifications, without departing from the spirit or scope of the invention or sacrificing any of its advantages, and we accordingly claim all such forms of the device to which we are 30 entitled.

Having thus described our invention, what we claim as new is:

1. In a refrigerating apparatus of the class described, a refrigerating compartment 35 and a plurality of refrigerating units arranged therein, each unit comprising a series of flues angularly disposed, with their side edges spaced from the walls of the compartment whereby to permit the free circulation 40 of air entirely about each flue and with the lower end of the flues of each unit

extending toward a common point within the compartment and a pipe coil arranged with each of said flues.

2. In a refrigerating apparatus of the 45 class described, a refrigerating compartment and a plurality of refrigerating units arranged therein, each of said units being formed of a plurality of division plates arranged in spaced parallel relation and constituting flues with their side edges spaced from the walls of the compartment whereby to permit the free circulation of air entirely about each flue and with the lower 50 ends thereof extending toward a common center of the compartment and a pipe coil arranged within each of said flues.

3. In a refrigerating apparatus of the class described, a refrigerating compartment and a plurality of refrigerating units suspended in the compartment and formed of a plurality of division plates arranged with their side edges in spaced relation from the walls of the compartment and in spaced 60 parallel relation with respect to each other whereby to prevent the free circulation of air entirely about each of said plates, said plates being further angularly disposed from a horizontal plane, the space between each of said division plates constituting 65 flues having their lower ends extending toward a common point within the compartment, a pipe coil arranged within the upper portion of each of the flues, the coils of each flue being connected with each other and means connecting the coils of the respective 70 units.

In testimony whereof we affix our signatures.

GEORGE T. SMILEY.
WALTER R. OHSE.
